UNITED STATES PATENT OFFICE

2,374,050

ELECTRIC CIRCUIT

Zoltan O. St. Palley, Pittsfield, Mass., assignor to
General Electric Company, a corporation of
New York

Application November 14, 1942, Serial No. 465,564

3 Claims. (Cl. 172—246)

This invention relates to electric circuits and more particularly to improvements in reactor control circuits.

As here used the term "reactor" means a device whose primary purpose is to insert either inductive or capacitive reactance into a circuit. It is generic to inductor and capacitor, the latter two being devices whose primary purpose is to insert inductance and capacitance respectively into a circuit.

There are many alternating-current circuits in which it is desirable to have adjustable reactance. For example, the power factor of alternating-current power circuits may be controlled by varying the amount of reactance which is connected across them.

In accordance with the present invention there is provided a novel and simple combination of a load-ratio-control transformer and a multi-tapped reactor for varying the reactive load on a circuit in equal volt-ampere steps. By "load ratio control" is meant tap changing under load, and the invention is further characterized by a very efficient use of the tap-changing equipment. This is accomplished by having the tap-changing equipment operate at its maximum values of rupturing voltage and continuous current-carrying capacity for all positions of the tap-changing equipment.

An object of the invention is to provide a new and improved electric circuit.

Another object of the invention is to provide a new and improved reactive volt-ampere control system.

A further object of the invention is to provide a new and improved power factor control system.

Still another object of the invention is to provide a new and improved load-ratio-control transformer and tap-changing reactor combination.

The invention will be better understood from the following description taken in connection with the accompanying drawing and its scope will be pointed out in the appended claims.

In the drawing Fig. 1 illustrates diagrammatically a simplified embodiment of the invention having inductors and Fig. 2 illustrates diagrammatically a more practical modification using capacitors.

Referring now to the drawing and more particularly to Fig. 1, there is shown therein an alternating-current circuit 1 across which is connected an autotransformer 2. The winding of this autotransformer is divided into a plurality of equal voltage sections by means of taps 3

brought out from the winding and terminating in stationary tap contacts 4.

For supplying lagging wattless kva. to the circuit there is provided a reactor in the form of a plurality of equal-size serially-connected inductors 5. The interconnections of these inductors are connected to taps 6 terminating in tap contacts 7. The inductors 5 may either be separate devices or they may be combined into a single winding from which the taps 6 are brought out.

Co-operating with the two sets of tap contacts 4 and 7 is a pair of bridging contacts 8 and 9 which are held in fixed spaced relation with respect to each other by an insulating member 10. This bridging contact assembly is movable as a unit along the path bounded by the two sets of contacts. For example, the insulating spacer member 10 may be internally threaded so as to constitute a traveling nut with respect to a rotatably threaded shaft 12 having a hand wheel 13 or other suitable means for rotating it. One terminal of the inductor is permanently connected to one terminal of the autotransformer as by connecting it directly to one side of the circuit 1.

The dimensions of all of the tap contacts are the same and their spacings are the same and are less than the distance between the outside edges of the bridging contacts 8 and 9 so that at least one of the bridging contacts 8 and 9 is always making a bridging connection between one tap contact 4 and its opposite tap contact 7.

The operation of Fig. 1 is as follows: Assume that circuit 1 is energized by any suitable source of alternating current (not shown) and that it is desired to change the amount of wattless lagging current supplied by the circuit to the transformer reactor combination shown in the drawing. For example, assume it is desired to decrease the amount of such current. Under these circumstances the shaft 12 is rotated in such a direction as to cause the contact assembly 8—9 to move downwardly as viewed in the drawing. After a short movement in this direction the bridging contact 8 will break connection between the opposite tap contacts 4 and 7, thus simultaneously cutting out one section of the secondary winding of the autotransformer and one section of the reactance. However, as the voltages of the transformer sections are equal and the values of the inductors are equal, the current through the bridging contact 9 remains the same as was the current through the bridging contact 8. Continued downward movement will bring both sets of bridging contacts into bridging relation with one pair of opposite tap contacts 4 and 7 which

will produce no change in the circuit. Eventually the bridging contact 8 will move out of contact with this pair of opposite tap contacts but again there will be no substantial change and all of the current will flow through the bridging contact 8. Further downward movement will then cause the bridging contact 8 simultaneously to make bridging connection between the lowermost pair of opposite tap contacts 4 and 7 and finally the bridging contact 8 will substantially simultaneously break the bridging connection between the next to the lowest opposite tap contacts 4 and 7. The result is that the next to the lowermost section of the secondary winding of the transformer is cut out of circuit and the next to the lowermost section of the reactor 5 is cut out of circuit, but here again there will be no change in the current through the bridging contacts because the voltage impressed across the reactor through the bridging contacts is always directly proportional to the reactance of the reactor which is in the circuit. Furthermore, as the only voltage which is interrupted is the tap-to-tap voltage between the transformer tap contacts 4, the rupturing duty on the tap-changing equipment will remain the same because the tap-to-tap transformer voltage is the same.

It will thus be seen that downward movement of the bridging contacts keeps the reactive current in the secondary winding of the transformer the same but lowers the effective voltage of the secondary winding. Therefore, the reactive volt-amperes of the secondary winding decrease as the bridging contacts are moved downwardly and consequently the reactive volt-amperes of the primary winding of the transformer must also decrease, only in that case the voltage is constant so it is the reactive lagging wattless current which decreases.

Similarly, rotating the driving wheel 13 in the opposite direction causes the bridging contacts to move upwardly, thereby successively to make bridging connection between opposite pairs of tap contacts whereby the effective voltage of the secondary winding of the transformer is increased in equal steps and is applied across variable amounts of the reactor whose reactance also increases in equal steps so that the secondary current and the current handled by the switching means always remains constant. Also, as the voltage ruptured by the switching means remains constant, it follows that the switching volt-ampere duty remains constant. However, upward movement of the bridging contacts causes the equipment as a whole to draw increasing amounts of lagging wattless current from the circuit 1.

In Fig. 2 the winding 2 is one of a plurality of insulated windings of a transformer 14. Two other windings of this transformer are shown at 15 and 16. These windings may, for example, be the primary and secondary windings of a power transformer whereby the winding 2 becomes the tertiary winding.

The reactor comprises a plurality of equal-size, serially-connected capacitors 5' provided with intermediate taps 6 and tap contacts 7.

Co-operating with the tap contacts 4 is a double-finger ratio adjuster having two movable ratio adjusting contacts 17 and 18 and similarly co-operating with the tap contacts 7 is another double-finger ratio adjuster having movable ratio adjusting contacts 19 and 20. These four ratio adjusting contacts may be moved in any suitable manner, such as by mounting them in-

dividually on traveling nuts which move along threaded rotating shafts 21, 22, 23 and 24 respectively. These shafts are all driven by a common operating mechanism shown schematically at 25. The contacts 17 and 18 are interconnected through an arcing duty contactor 26, and the contacts 18 and 20 are interconnected through an arcing duty contactor 27. These contactors are similarly driven by the operating mechanism 25 and all of the contacts and contactors are so interlocked that contactors 17 and 18 move simultaneously but only when arcing duty contactor 26 is open, and contactors 18 and 20 move simultaneously but only when arcing duty contactor 27 is open. In this manner the ratio adjusting contacts 17, 18, 19 and 20 need perform no arcing

In order to double the number of steps obtainable with the equipment shown in Fig. 2 the transformer is provided with a tickler winding 28 whose voltage is half the voltage difference between the taps 3 and the reactor is provided with an auxiliary capacitor 29 whose capacitance is twice that of the capacitors 5' or, in other words, its capacitive reactance is one-half the capacitive reactance of the reactors 5'. These latter two devices enable voltages and reactance values to be obtained which are half way between those obtainable with the tap contacts 30 alone.

The operation of Fig. 2 is as follows: With contactor 26 closed and contactor 27 open there will be four capacitors connected across four tap sections of the winding 2. If now contactor 27 is closed and contactor 26 is opened there will, in effect, be four and one-half capacitors connected across four and one-half sections of the winding 2, thereby raising the capacitive volt-amperes by an amount equal to one-half a step or tap change. If while contactor 27 is closed and contactor 26 is opened the ratio adjusting contacts 17 and 19 are moved downwardly to the next tap contacts 4 and 7 respectively, then arcing contactor 27 is opened and contactor 26 is closed the connections will be such that five capacitors will be connected across five tap sections of the winding 2, thus further increasing the capacitive volt-amperes. In this manner the tap changes may be made step by step but twice as many steps may be obtained as there are taps.

As in Fig. 1 the arcing duty on the contactors 26 and 27 remains the same for all positions of the ratio adjusting contacts provided, of course, that they are moved step by step and always engage corresponding contacts in the winding and the reactor.

The arcing duty contactors are not essential to the invention and in cases where the ratio adjusting contacts can safely withstand the arcing duty these arcing duty contactors 26 and 27 may be dispensed with.

From the above description it will be seen that there has been provided an arrangement wherein standard (equal) transformer tap spacings and standard load-ratio-control mechanisms may be combined with a plurality of equal-size serially-connected reactors so as to obtain variations of reactive volt-amperes in equal steps, these steps being characterized by constant current and equal step voltage changes in the secondary circuit and constant voltage with equal step current variations in the primary circuit.

While there have been shown and described particular embodiments of this invention, it will be obvious to those skilled in the art that various

changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. In combination, a transformer winding, a plurality of serially-connected reactors which receive their entire energization from said transformer winding, and means for selectively connecting any desired number of said serially connected reactors across such variable portions of said winding that the voltage of such portions is directly proportional to the reactance connected thereacross whereby the current in said connecting means is constant.

2. In combination, a transformer having a winding divided into a plurality of equal-voltage serially-connected sections, a like number of

equal-size reactors which receive their entire energization from said transformer winding, said reactors being connected in series, and means for selectively connecting any desired number of said reactors across the same number of said sections.

3. In combination, a transformer having a winding provided with a set of electrically equal-spaced taps, a plurality of electrically equal reactors which receive their entire energization from said transformer winding, said reactors being connected in series with each other, a set of taps connected to the interconnections between said reactors, and tap-changing means for selectively interconnecting taps in the two sets, said interconnection being between pairs of taps whose combined voltage and reactance values are directly proportional to each other whereby the reactive current in said tap-changing means is constant for any positions thereof.

ZOLTAN O. ST. PALLEY.
